2 SHEETS—SHEET 2.

UNITED STATES PATENT OFFICE.

JOHN R. BALL, OF DURANGO, COLORADO.

INCLOSED-SCREEN BALL-MILL.

1,337,033.

Specification of Letters Patent. Patented Apr. 13, 1920.

Application filed April 24, 1919. Serial No. 292,343.

To all whom it may concern:

Be it known that I, JOHN R. BALL, a citizen of the United States, residing at Durango, in the county of La Plata and State 5 of Colorado, have invented certain new and useful Improvements in Inclosed-Screen Ball-Mills; and I do declare the following to be a full, clear, and exact description of the invention, such as will enable others 10 skilled in the art to which it appertains to make and use the same.

My invention relates to that class of ore grinding mills commonly known as ball mills. Heretofore machines of this type 15 have been provided having passages for discharging the ground ore from the discharge screen into a hollow trunnion from which final discharge takes place, but in all of such mills with which I am familiar, the 20 screen has been entirely accessible only from the interior of the mill, for repairing when necessary or for the installation of a new screen. This usually requires that a large part of the mill shall be torn down, thus 25 necessitating that it be idle for considerable time which means great loss in time and output. The principal object of my invention is to overcome this difficulty by providing screens which are totally accessible 30 from the exterior of the mill by simply removing a cover-plate, and it has been found that by this arrangement, the screen can be replaced or repaired in less than half the time previously required.

35 The grinding cylinder is provided on its discharge end with a plurality of radial reinforcing ribs extending from the hub to the periphery, and another object of the invention is to utilize these ribs, together with 40 a removable plate or plates, to form independent pockets into which the screens discharge the pulverized ore.

With the foregoing in view, the invention resides in the novel features of construction 45 and unique association of parts hereinafter fully described and claimed, reference being made to the accompanying drawings.

Figure 1 is a side elevation with parts broken away and in section to show the improved features.

Fig. 2 is an end elevation of the grinding cylinder removed from its bearings, parts being broken away and in section.

In the drawings above briefly described, 55 the numeral 1 designates a rotating cylinder of a ball mill, one end of such cylinder

having a trunnion 2 supported in a bearing 3 and provided with the usual spiral collecting head 4 which raises the ore laden slime and feeds the same into the cylinder 1 60 through the trunnion 2, no claim being made in the present application to any of these parts.

The numeral 5 designates the end wall of the cylinder 1 opposite the trunnion 2, said 65 end wall having a hollow trunnion shown as including a hub 6 integral with said wall and provided with an annular outstanding flange 7 to which the inner end of a detachable trunnion member 8 is secured by bolts 70 or the like 9. The outer side of the end wall 5 is provided with a plurality of radial ribs 10 leading from the hub 6 to the peripheral portion of said plate for reinforcing the 75 same, and screens 11 are provided in the plate 5 between the several ribs, said screens being detachably secured in place by any preferred means such as the plates 12 and screws 13 shown. The inner sides of the screens may well abut an end lining 11^a 80 having openings at said screens and the hub 6.

An annular cover-plate 14 preferably formed in sections, as indicated in Fig. 2, is 85 detachably secured to the outer edges of the ribs 10 by cap screws or the like 15, said cover-plate having a central opening 16 receiving the flange 7 of the hub 6. End plates 17 extend between the outer ends of the ribs 10 and by screws or other preferred 90 fasteners 18, are secured to lugs 19 formed on opposite sides of said ribs, and if desired the plates 17 may be additionally secured to the peripheral edge of the plate 14 by other screws 20. The ribs 10, the plate 14, and the 95 plates 17 coöperate to form a plurality of radial pockets 21 into which the ground ore is discharged through the screens 11, and by means of openings 22 in the hollow hub 6, said pockets discharge such ore into 100 the hollow trunnion, from which the final discharge takes place. A tube 23 forming a core is shown in the hollow trunnion 6—8, the periphery of said core having longitudinal grooves 24 registering at their inner 105 ends with the openings 22, to receive the discharged ore and carry it to the outer end of the trunnion 6—8. Core 23 is preferably hollow to decrease weight.

By the construction shown and described, 110 whenever it is necessary to repair or replace any of the screens 11, access thereto may be

quickly and easily had by removing the plate 14 and possibly the end plates 17, so that little time is necessary, with the result that the mill need not be out of operation 5 for any appreciable time. This is a highly important advantage as is also the ease with which access may be had to the screens.

Since probably the best results are obtained from the details disclosed, they may 10 well be followed, but within the scope of the invention as claimed, minor changes may well be made. Also, it will be understood that the form of screen may vary and that it may be of any required mesh. Furthermore, the mill may be used for grinding 15 cement and numerous other materials as well as ore.

I claim:—

1. In an ore grinding mill, a grinding cylinder having a hollow trunnion joined directly to one of its end walls, reinforcing ribs on the outer side of said end wall radiating from the inner end of said trunnion, discharge screens between said ribs, plate 20 means spaced outwardly from said end wall and free of permanent connection with said trunnion, said plate means being detachably secured at the outer edges of said ribs, and additional plate means extending across the 25

spaces between the outer ends of said ribs, 30 all of said plate means coöperating with said ribs to form a plurality of pockets at the outer side of said end wall, into which said screens discharge, said first named plate means being detachable without detaching 35 said end wall to give access to said screens, the inner ends of the aforesaid pockets having openings for conducting the discharged ore into said trunnion.

2. In an ore grinding mill, a grinding cylinder having a hollow hub extending from one of its end walls, a plurality of reinforcing ribs on the outer side of said wall and radiating from said hub, screens between 40 said ribs, plate means secured to the outer edges of said ribs and extending between them, additional plate means between the outer ends of the ribs, all of said plate means coöperating with said ribs to form 45 pockets into which the screens discharge, the hub having openings leading from said pockets into its interior, and a tubular trunnion member extending outwardly from said hub.

In testimony whereof I have hereunto set 50 my hand.

JOHN R. BALL.
